BODY MOUNTED BULLDOZER

Harry H. Washbond, Springfield, Ill., assignor, by mesne assignments, to Allis-Chalmers Manufacturing Company, a corporation of Delaware

Application May 9, 1951, Serial No. 225,363

12 Claims. (Cl. 37—144)

This invention relates to implement equipped vehicles, such as bulldozers, angle dozers, snow plows, and the like, which are placed at the desired operating level by swinging the vehicle body relative to the vehicle supports.

More specifically this invention relates to a body-mounted bulldozer having the dozer blade affixed to the front end of a tractor and raised and lowered with the front end of the tractor body by fluid pressure actuated jacks acting between the tractor and the tractor track frames.

The invention will be hereinafter specifically described as embodied in a bulldozer, but it should be understood that the principles of this invention are generally applicable to other types of earth or snow moving equipment mounted on vehicles such as tractors or the like.

Heretofore, bulldozer blades have been carried on push beams which are pivotally mounted on a tractor. The push beam mounted blade was swung relative to the tractor by means of actuators such as cables, fluid pressure actuated jacks, or other linkages. In all of these heretofore known push beam mounted bulldozer blade arrangements, the blade had to be positioned sufficiently forward from the front end of the tractor so that it could be swung through its operating arc without striking or rubbing against the tractor. The resulting forward spacing of the implement blade interfered with the fore and aft operating balance of the tractor, and placed heavy strains on the tractor parts. Further, when the blade was operated at high levels, the view of the operator was substantially obstructed. Similar clearances had to be provided between the swinging push beams and the tractor, thereby increasing the over-all width as well as the over-all length of the assembly. The dozer blade had to be made sufficiently wide to extend at least up to the front ends of the push beams and it was not possible to design the blades of desired height without creating a pushing frontal area in excess of the available pushing force of the tractor.

The present invention now eliminates all of the aforementioned objections and provides a bulldozer assembly free from push beams. According to this invention, the dozer blade is fixedly mounted on the front end of the tractor body. In a conventional tractor, the body pivots around rear axles supported by track frames carrying the crawler tracks therearound. A transverse spring having its ends carried on the track frames underlies the tractor body to support the front end thereof. In accordance with this invention, the tractor spring is removed and the front end of the tractor body is adjustably supported on the track frames by fluid pressure actuated jacks. These jacks are mounted on the sides of the tractor body and act on torsion absorbing levers which are linked to the track frames. The lever arrangement eliminates loads on the track frames which would tend to tip them inwardly and thereby avoids the necessity for modifying existing tractor structure.

The bulldozer assembly of this invention can have a dozer blade of any desired width or height, since it does not need to extend in front of any push beam mounting.

2

The assembly is free from any extensions with increase the width of the tractor and, since the blade is adapted to be mounted flush against the front end of the tractor, the fore and aft balance of the tractor is not disturbed.

5 An important feature of the invention resides in direct utilization of the full weight of the front end of a tractor body for digging pressure on a dozer blade.

Another feature of the invention resides in the utilization of substantially the full combined weights of the 10 front ends of the tractor body and track assemblies for digging pressure on the dozer blade.

Another feature of the invention resides in the provision of a bulldozer which has a blade swingable through a wide arc without ever obstructing the view of the 15 operator.

An object of the invention is to provide earth or snow moving equipment which operates as an integral part of a vehicle body.

Another object of the invention is to provide a bulldozer or the like tractor machine having an implement carrying body swingable about its supporting frame in response to operation of fluid pressure controlled jacks bottomed on the supporting frame.

A further object of the invention is to provide a tractor 25 with hydraulic jacks operatively connected between the tractor body and the tractor track frames to swing the front end of the tractor body without placing a torsion load on the track frames.

A still further object of the invention is to provide a 30 bulldozer free from push beams and other linkages which increase the over-all width of the machine.

A still further object of the invention is to provide a bulldozer having a blade frame affixed to the front end of a tractor body and pivotally supporting hydraulic 35 jacks at the sides of the body which act on the front ends of the tractor track frames through shiftable links accommodating a substantially direct lift of the body irrespective of the degree of inclination of the body relative to the track frames.

40 A further object of the invention is to provide a narrow width bulldozer machine which will push as much earth as a wider machine by virtue of the increased height of the dozer blade and which will have an enhanced digging capacity because of its reduced width.

45 A still further object of the invention is to provide a bulldozer which has a blade mounted directly on the front end of the tractor body close to the tractor tracks, thereby providing a quick digging approach.

Other and further objects of the invention will be 50 apparent to those skilled in the art from the following detailed description of the annexed sheets of drawings which, by way of preferred examples only, illustrate several embodiments of the invention.

On the drawings:

55 Figure 1 is a side elevational view of one form of bulldozer machine according to the invention and illustrating in dotted lines a raised position of the machine.

Figure 2 is a plan view of the machine of Figure 1.

60 Figure 3 is a phantom view illustrating the fully raised and lowered positions of the machine to better show the substantially direct lift application of the hydraulic jack.

Figure 4 is a diagrammatic view illustrating the manner in which the hydraulic jacks are in intercommunication.

65 Figure 5 is a side elevational view similar to Figure 1 but illustrating a modified arrangement wherein the weight of the track assemblies can be added to the digging force of the dozer blade.

70 Figure 6 is a fragmentary plan view of the linkage between the tractor body and track frames in the machine of Figure 5.

Figure 7 is a vertical cross-sectional view, with parts in elevation, taken along the line 7—7 of Figure 6.

Figure 8 is a diagrammatic view similar to Figure 4 illustrating the manner in which the hydraulic jacks of the embodiment of Figure 5 are placed in intercommunication.

As shown on the drawings:

The bulldozer machine 10 of Figures 1 to 3 includes a crawler type tractor 11 having a main body 12 and crawler track assemblies 13, 13 on each side of the main body. The body 12 includes an engine radiator 14 at the front end thereof, a hood 15 under which is mounted an internal combustion engine (not shown). A driver's seat 16 is provided at the rear end of the body. Axles 17, 17 project laterally thru gear casings at the rear end of the body and are fixedly supported by the body. Brackets 18 are swingably mounted on the inner ends of the axles 17 and brackets 19 are swingably mounted on the outer ends of these axles. Driving gears 20 driven by the engine are also rotatably mounted on the axles between the brackets 18 and 19.

The crawler track assemblies 13 each include an inner track frame 21 having its rear end carried by bracket 18 and an outer track frame 22 having its rear end carried by the bracket 19. The inner and outer frames are in spaced parallel horizontal relation and afford supports for bottom load carrying idler rollers 23 (Figure 1), a track tightening assembly 24, and a front pulley roll 25 acted on by the assembly 24. An endless belt 26 of crawler tracks is trained around the gear 20 and roll 25 and under the rollers 23 along its lower run. An idler guide roll 27 is also carried by the inner track frame 21 to support the upper run of the crawler tracks as it passes between the gear 20 and front roller 25.

The track assemblies 13 are independently swingable about the axles 17 relative to the tractor body 12 and the track frames 21 and 22 of each assembly are integrally connected as a unit.

In conventional tractors, a transverse spring is mounted under the tractor body 12 and is supported at its ends on the inner track frames 21 near the front roller 25. In accordance with this invention, however, the conventional tractor spring is dispensed with and in its place there is provided a bracket 28 on each inner track frame 21 in the same position usually occupied by the bracket for the end of the tractor spring. Each bracket 28 has an upstanding ear straddled by metal links 29 which are pivoted to the ear by means of a pin 30. The upper ends of the links 29 terminate in spaced relation beneath the upper run of the crawler tracks 26 and the links have sufficient clearance between the assembly 24 and the adjoining bearing support for the front roller 25 that they can swing about the pin 30 through an appreciable arc without striking any adjacent tractor structure.

A bulldozer blade and frame unit or attachment 31 is mounted on the front end of the tractor body 12 and includes a blade 32 extending transversely across the front end of the tractor and terminating substantially flush with the outer ends of the track assemblies 13. The blade 32 is backed by suitable reinforcing framework 33. A pair of arms or brackets 34 integrally affixed to the framework 33 extend rearwardly from the blade to straddle both sides of the tractor body 12. Each bracket 34 extends to a position adjacent the bracket 28. Each bracket 34 has an outturned top flange 34a around its upper edge and extending across its rear face. An angle bracket 35 secured, as by the welding or the like, on the main side beam 12a of the tractor body 12 has an outturned leg backing up the rear face of the flange 34a and bolted thereto by means of bolts 36.

Additional bolts 37 (Figure 2) also connect the flat vertical face of the bracket 34 to the main body frame beam 12a.

Each bracket 34 has a vertical extension alongside of the tractor engine hood 15 and the upper end of this ex-

tension has an integral depending ear 34b on which is pivotally suspended a hydraulic jack 38. A pivot pin 39 connects the top end of the cylinder or upper portion 38a of the jack 38 to the ear 34b and the piston 38b of the jack depends from the bottom end of the cylinder 38a. The jack 38 is free to swing through a limited arc between opposite flanges 34a of the bracket 34.

Ears or lugs 40 on the frame 33 carry a pin 41 extending laterally outward from each bracket 34 at the front end thereof.

A lever 42 is provided along the outer face of each bracket 34 and has a front end boss pivotally mounted on the pin 41. The lever 42 extends rearwardly in spaced parallel relation with the face of the bracket 34 under the hydraulic jack 38 and then turns outwardly along an inclined leg portion 42a thereof to a rearwardly extending flattened ear portion 42b disposed above the inner track frame 21 and fitting between the links 29. A pivot pin 43 connects the links with the ear 42b. The lever 42 is thereby pivotally supported at its front end on the frame 33 and at its rear end on the links 29 which can pivot about the pin 30 carried by the bracket 28.

An ear 44 is provided on top of the lever 42 ahead of the offset portion 42a thereof and is pivotally connected by a pin 45 to an ear 38c on the lower end of the piston or lower portion 38b of jack 38. The hydraulic jack 38 thereby has the upper end of its cylinder pivoted to the upper end of the bracket 34 and the lower end of its piston pivoted to a rear end portion of the lever 42.

The blade assembly 31 has the blade 32 thereof immediately in front of the engine radiator 14 and since the assembly is integrally affixed to the tractor body with no provision for relative movement therebetween, no clearance need be provided between the radiator and blade, and the blade is therefore carried closer to the front ends of the crawler tracks 26 than has heretofore been possible. The assembly 31, in effect, straddles the front end of the tractor body and serves to reinforce and brace the body.

The upper ends of the jack cylinders 38a have nipples 46 for flowing hydraulic fluid through the cylinders above the pistons 38b. Each nipple 46 is connected with a flexible hose 47. Each hose 47, in turn, is connected to a T fitting 48 having the third leg thereof coupled to a hose or tube 49. As best shown in Figure 4, a valve 50 controls flow of hydraulic fluid from a pump 51 fed by a tank 52 which is carried on the tractor body. A return conduit 53 is provided between the valve and tank for return of hydraulic fluid such as oil back to the tank.

Hydraulic fluid can always flow freely between the cylinders 38a through the T coupling 48 which places the cylinders in fluid intercommunication. Fluid is also supplied under equal pressure to the top of each piston 38b.

As the pistons 38b are extended, being forced downwardly out of the lower ends of the cylinders 38a under the influence of hydraulic pressure, an elongation is provided in the only linkage connecting the front end of the tractor body with the front ends of the track assemblies, and the body 12 is swung about its axle pivots to raise the blade assembly 31 therewith as best illustrated in Figures 1 and 3. Conversely, the jacks 38 are contracted when the valve 50 is set so as to allow return of the hydraulic fluid to the tank 52, the weight of the body forcing the pistons 38b back into the cylinders 38a, thereby shortening the linkage between the track assemblies and the body and allowing the body to swing downwardly.

During the pivoting of the body about its axles 17 relative to the track assemblies, the links 29 will swing as illustrated in Figures 1 and 3 to accommodate the shifting position of the rear end of the lever 42 due to the changing position of the lever pivot 41 relative to the link pivot 30. It will be noted that the hydraulic jack 38 remains in a substantially upright position throughout the full extent of the swinging movement of the tractor body to apply an effective lift to the body without straining the pivot connections. Since the jack is connected to the

lever 42 closely adjacent the points of connection of the lever with the track frame, a substantially direct lift effect is obtained.

The lever 42 serves a very important function in relieving the track frame 21 from torsion loads tending to tip the frame inwardly under the load influence of the tractor body and blade assembly. This torsion load is transmitted by the lever 42 into the pivot pin connection 41 where it is resisted, so that the load is applied to the track frame in a straight vertical direction. The assembly therefore makes possible positioning of the lifting jacks 38 in an out of the way position between the tractor body and the track assemblies without creating a torsion load on the track assemblies.

As best shown in Figure 3, the blade assembly 31 has a wide range of operating positions from a low level position which is well below the lower run of the crawler tracks to a high position which is substantially above ground level. The invention makes it relatively simple to design the blade assembly so that it can be moved through a range of at least 13 inches below ground level to 30 inches above ground level. At the same time, the level of the driver's seat 16 is not appreciably changed, since the seat 16 is almost directly over the pivot support axles 17 for the tractor body. Since the blade assembly 31 is affixed to the front end of the tractor body and terminates at a level below the top of the engine hood 15, the operator on seat 16 always has a full unobstructed view of the blade operation, even in the high level position of the blade.

The hydraulic jack connection between the tractor track frames and the tractor body coupled with the non-movable fixed connection between the blade assembly and the front end of the tractor body provides for maximum digging pressure on the bulldozer blade, because the full dead weight of the front end of the tractor body including the heavy engine carried at the front end is directly applied to the blade. This has heretofore not been possible in prior known bulldozer machines.

As best shown in Figure 2, the bulldozer blade 32 does not project laterally beyond the outer faces of the track assemblies 13 and a narrow width bulldozer machine is thereby provided with no obstruction at the sides. At the same time, however, the blade 32 can have the full earth moving capacity of a wider blade, because it can be increased in height without projecting above the radiator. Ample frontal area of the radiator is thereby always exposed for efficient cooling of the engine.

The bulldozer machine 10a of Figures 5 to 8 operates on the same principle as the above described machine 10, but provides for the addition of the weight of the track assemblies 13 to increase the digging pressure of the blade assembly 31. In Figures 5 to 8, parts identical with parts described in Figures 1 to 4 have been marked with the same reference numerals.

As best shown in Figures 5 and 6, the blade assembly or attachment 31 has rearwardly extending relatively flat bracket plates 60 straddling each side of the tractor body 12 and affixed to the outer face of the main body beam 12a as by welding or other suitable means. An outturned triangular gusset 61 reinforces the frame 33 and bracket plates 60. The bracket plate 60 does not project above the side body beam 12a.

A cylindrical rod or tube 62 has the front end thereof pivotally supported on the pin 41 carried by the lugs or ears 40 of the blade assembly 31 and projects rearwardly therefrom in parallel relation with the side beam or bracket plate 60 to an outturned portion 62a terminating in a parallel offset end 62b which is just inwardly from the inner track frame 21.

As best shown in Figure 7, this offset end 62b has a boss 62c on its outer face carrying a laterally extending stud 63 which projects over the track frame 21. A spherical bearing 64 is carried on the stud and swivelly supports a link 65. A nut 66 threaded on the stud 63 holds the bearing and link in position.

A bracket 67 on the track frame 21 at the same location where the ends of the conventional tractor spring would normally be mounted has a pair of upstanding ears receiving the lower end of the link 65 therebetween. A pivot pin 68 pivotally connects the link with the bracket 67. The lever 62 therefore is pivotally supported at its front end on the blade assembly 31 in the same manner as described in connection with the bulldozer machine 10, but the offset end of the lever 62b is connected ahead of its rear end through a swivel connection with a link that can shift in response to variations in the distance between the pivot pin 41 and the bracket 67 as the tractor body pivots about its rear axle. As in the bulldozer machine 10, the lever 62 serves as does lever 42 (Fig. 5) to transmit torsion loads to be resisted by the pin 41 which would otherwise tend to tip the track frame 21 inwardly.

The rear end of the offset lever portion 62b is provided with a boss 62d on its inner face in spaced rearward relation from the boss 62c. This boss 62d has a laterally projecting stud 69 carrying a spherical bearing 70 which is held thereon by means of a nut 71 threaded on the stud.

The main frame 12a of the tractor body 12 has a reinforcing apertured spacer plate 72 affixed to the outer face thereof behind the plate 60. A cylinder mounting bracket 73 having a stud 74 projecting into the aperture of the plate 72, is bolted to the plate by means of bolts 75. The bracket 73 has spaced parallel outturned flanges 73a with bearing bosses at the upper ends thereof pivotally supporting studs 76 of a ring 77 disposed between the flanges. The ring 77 surrounds the cylinder 78a or upper portion of a hydraulic jack 78 and the cylinder is pivotally mounted in the ring on studs 79. A universal joint connection is thereby provided between the cylinder 78a and the bracket 73.

The hydraulic jack 78 has a piston 78b slidably mounted therein with a piston rod 78c or lower portion projecting through the lower end of the cylinder 78a and carrying a lug 78d at its lower end swivelly receiving the sphere 70 so as to connect the piston rod with the rear end of the lever 62.

Each hydraulic jack 78 has a nipple 80 communicating with the upper end of the cylinder 78a thereof. A similar nipple 81 communicates with the lower end of the cylinder. Each nipple 80 receives a flexible hose 82 as best shown in Figure 8 which is connected to a T fitting 83. Flexible hoses 84 connect the nipples 81 with a T fitting 85. Hoses or pipes 86 and 87 respectively connect the T fittings 83 and 85 with a valve 88. A pump 89 supplies hydraulic fluid from a tank 90 to the valve 88. A fluid connection 91 between the valve and the tank 90 provides for return flow of the hydraulic fluid. The upper ends of the cylinders 78 are thereby in free fluid intercommunication through the fitting 83. The lower ends of the cylinders are likewise in fluid intercommunication through the fitting 85. The hydraulic jack 78 is double acting and is further definable as being extensible and contractible. The valve 88 can be manipulated to positively force the pistons 78b either upwardly thereby extending the jack 78 or downwardly thereby contracting the jack 78 in the cylinder 78a but in either instance the same pressures will be applied to each piston 78b due to the intercommunication between the cylinders 78a. Since the piston rods 78c are swivelly connected with the rear ends of the levers 62, which levers, in turn, are connected through the links 65 with the track frames 21, a raising and lowering of the pistons 78b by the hydraulic fluid will shorten or elongate the only connections between the front ends of the track frames and the front end of the tractor body, so that the tractor body will be caused to swing about its pivot axles 17 as shown in Figure 5. However, since the pistons 78b can also receive fluid on their lower faces and thereby force the pistons 78b upwardly in the cylinders, it is possible

70 to add the weight of the front ends of the track assem-

blies 13 to the weight of the front end of the tractor body 12 for application at the blade assembly 31 as best illustrated in Figure 5. As therein shown in solid lines, up pressure on the hydraulic jacks will serve to raise the front ends of the crawler tracks from their dotted line position, thereby adding the weight of these front ends to the digging point of the blade 32. When the fluid pressure is applied to the top ends of the pistons in the jacks 78, the piston rods 78c will be moved outwardly from the cylinders and the tractor body will be raised to the dotted line position. In this position, the digging pressure in the blade is not influenced by the weight of the track assemblies, since the tracks will be in full contact with the ground along their bottom run, as shown in dotted lines.

The swivel connections between the piston rods and the levers, and between the levers and the links will allow for misalignment without stressing the connected parts. These swivel connections function as torque absorbing joints in that they provide added insurance against transmission of torsion loads to the track frames, since twisting movements of the lever cannot be transmitted through these joints.

From the above descriptions it will therefore be understood that this invention provides a body mounted bulldozer wherein a bulldozer blade assembly is fixedly mounted on the front end of a tractor body to move as a unit therewith and wherein either single acting or double acting upright hydraulic jacks form the only connections between the front end of the tractor body and the front ends of the tractor track assemblies for swinging the body about the pivots between the track assemblies and the body. The jacks act with straight line forces in substantially vertical planes between the tractor body and track frames. Linkages between the tractor body and track frames prevent transmission of torsion loads to the track frames, so that specially designed tractor parts or reinforcements are not necessary.

It will be understood that modifications and variations may be effected without departing from the scope of the novel concepts of the present invention.

I claim as my invention:

1. A bulldozer comprising a tractor having a body, a crawler track assembly on each side of the body, pivot means connecting the rear end portions of the body and track assemblies, each track assembly having a pair of horizontally aligned spaced parallel longitudinal track frames, a blade assembly secured to the front end of the body and extending laterally in front of the track assemblies, a lever between each side of the body and the adjacent crawler track assembly, torque resisting horizontal pivots on the rear face of the blade assembly mounting said levers for swinging movement in a vertical plane only, an offset portion on the rear end of each lever extending over the adjacent inner track frame, a swingable link pivoted on the top face of each inner track frame and extending upwardly thereof, a swivel torque absorbing joint connecting the upper end of each link with the offset end of the adjacent lever, and an upright hydraulic jack pivotally interposed between the lever and body for direct lift action on the body to swing the blade and body about the pivot means without subjecting the inner track frames to torsion loads tending to tip the frames inwardly.

2. In a bulldozer the combination of a tractor having a body; a crawler track assembly on each side of said body; pivot means connecting the rear end portions of said body and track assemblies, said track assemblies being in parallel relationship to one another and each having a track frame; an earth-working tool assembly secured to the front end of the body and extending laterally in front of said track assemblies; and a pair of raising and lowering mechanisms operatively interposed between said body and said track assemblies, respectively, each of said mechanisms comprising: a tor-

sion lever having one end connected to said body for vertical swinging movement about a horizontal axis and having an elongated torque transmitting portion extending longitudinally of said tractor from said one end in transverse relation to said horizontal axis; connecting means for attaching said torque transmitting portion in vertical load transmitting relation to the track frame of the adjacent track assembly; an upright jack having a pair of relatively extensible and contractible elements, 10 said jacks being disposed, respectively, between said body and said track assemblies; attaching means connecting one of said elements to said one side of said body; and attaching means pivotally connecting the other of said elements to said lever at a point spaced from said connecting means in the direction of said horizontal axis.

3. In a bulldozer the combination of a tractor having a body; a crawler track assembly on each side of said body; pivot means connecting the rear end portions of said body and track assemblies, said track assemblies 20 being in parallel relationship to one another and each having a track frame; an earth-working tool assembly secured to the front end of the body; and a pair of raising and lowering mechanisms operatively interposed between said body and said track assemblies, respectively, 25 each of said mechanisms comprising: a torsion lever having one end connected to said body for vertical swinging movement about a horizontal axis disposed in transverse relation to said tractor, said lever having an elongated torque transmitting portion intermediate its opposite ends disposed between said body and the adjacent track assembly; connecting means for attaching said lever in vertical load transmitting relation to the track frame of the adjacent track assembly; an upright jack disposed between said body and the adjacent track 30 assembly and having a pair of relatively extensible and contractible elements; attaching means pivotally connecting one of said elements to said one side of said body; and attaching means pivotally connecting the other of said elements to said lever at a point spaced from said connecting means in the direction toward said body, the line of thrust transmitted by said jack to said lever lying substantially in a vertical plane parallel to said track assemblies.

4. The bulldozer set forth in claim 3 wherein the connecting means for attaching said lever to the track frame includes a universal pivot connection.

5. The bulldozer set forth in claim 4 wherein the attaching means for pivotally connecting the other of said elements to said other end of said lever includes a universal pivot connection.

6. In a bulldozer the combination of a tractor having a body; a crawler track assembly on each side of said body; pivot means connecting the rear end portions of said body and track assemblies, said track assemblies being in parallel relationship to one another and each having a track frame; an earth-working tool assembly secured to the front end of the body; and a pair of raising and lowering mechanisms operatively interposed between said body and said track assemblies, respectively, each of said mechanisms comprising: a torsion lever having one end connected to said body for vertical swinging movement about a horizontal axis and having an elongated torque transmitting portion intermediate its opposite ends extending longitudinally of said tractor in transverse relation to said horizontal axis, said lever having an offset part at its other end extending in overlying relation to said track frame of the adjacent track assembly; connecting means for attaching said offset part in vertical load transmitting relation to said track frame of the adjacent track assembly; an upright hydraulic jack disposed between said one side of said body and the adjacent track assembly and having a piston element and a cylinder element; attaching means pivotally connecting one of said elements to said one side of said body; and attaching means pivotally connecting the other of

said elements to said other end of said lever at a point spaced from said connecting means in the direction toward said body.

7. In a bulldozer the combination of a tractor having a body; a crawler track assembly on each side of said body; pivot means connecting the rear end portions of said body and track assemblies, said track assemblies being in parallel relationship to one another and each having a track frame; a blade assembly secured to the front end of the body and extending laterally in front of said track assemblies; and a pair of raising and lowering mechanisms operatively interposed between said body and said track assemblies, respectively, each of said mechanisms comprising: a torsion lever having one end connected to said body for vertical swinging movement about a horizontal axis and having an elongated torque transmitting portion intermediate its opposite ends extending longitudinally of said tractor in transverse relation to said horizontal axis, said lever having an offset part at its other end extending in overlapping relation to said track frame of the adjacent track assembly; a vertically disposed link having one of its opposite ends pivotally connected to said offset part and having the other of its ends pivotally connected to said track frame of the adjacent track assembly; an upright hydraulic jack disposed between said one side of said body and the adjacent track assembly and having a piston element and a cylinder element; attaching means pivotally connecting one of said elements to said one side of said body; and attaching means pivotally connecting the other of said elements to said other end of said lever at a point spaced in the direction toward said body from the connection between said link and track frame.

8. In a crawler tractor of the type having endless track running gear at each of its lateral sides, the combination comprising: a main body assembly; a track frame assembly for an endless track disposed at one side of said main body assembly; a first means pivotally connecting said track frame assembly to one side of said main body assembly for swinging movement about a rearwardly disposed transverse axis; an attachment rigidly secured to the forward end of said main body assembly including an earthworking tool disposed forwardly of said running gear; a horizontally disposed lever; a vertically disposed link having one end pivotally connected to said lever and having its other end pivotally connected to one of said assemblies; a second means pivotally connecting said lever to the other of said assemblies at a point spaced horizontally from the connection between said link and said one of said assemblies; and a vertically disposed extensible and contractible jack having its upper portion pivotally connected to said main body and its lower portion pivotally connected to said lever.

9. In a crawler tractor of the type having endless track running gear at each of its lateral sides, the combination comprising: a main body assembly; a track frame assembly for an endless track disposed at one side of said main body assembly; means pivotally connecting said track frame assembly to one side of said main body assembly for swinging movement about a rearwardly disposed transverse axis; an attachment rigidly secured to the forward end of said main body assembly including an earthworking tool disposed forwardly of said track frame assembly; a horizontally disposed lever; a vertically disposed link having one end pivotally connected to said lever and having its other end pivotally connected to one of said assemblies; means pivotally connecting said lever to the other of said assemblies at a point spaced horizontally from the connection between said link and said one of said assemblies; and a vertically disposed extensible and contractible hydraulic jack having its upper portion pivotally connected to said main body and its lower end pivotally connected to said lever, said jack being positioned so that its line of thrust passes between said main body assembly and said track frame assembly.

10. The combination as set forth in claim 8 wherein: said vertically disposed link has one end pivotally connected to said track frame assembly; and said second means pivotally connects said lever to said main body assembly.

11. The combination set forth in claim 10 wherein: said attachment includes a mounting bracket rigidly secured to and extending rearwardly from said earth working tool, said bracket being releasably secured to said main body assembly; said second means pivotally connects said lever to said attachment at a point spaced horizontally from said rearwardly disposed transverse axis; and said extensible and contractible jack has its upper portion pivotally connected to said bracket at a location spaced horizontally from said point and axis.

12. The combination set forth in claim 11 wherein: said earth working tool, said bracket, said lever and said extensible and contractible jack comprise a unitary removable attachment; and said combination includes a means for releasably securing said attachment on said main body assembly.
